Primary Examiner—Brian N. VinsonAttorney, Agent, or Firm—Rhodes, Coats & Bennett*[57]*CLAIM

The ornamental design for a TV canopy, as shown and described.

DESCRIPTION

FIG. 1 is a top, bottom, front, and right side perspective view of a TV canopy showing my new design;

FIG. 2 is a front elevational view thereof;

FIG. 3 is a rear elevational view thereof;

FIG. 4 is a right side elevational view thereof, the left side being a mirror image of that shown; and,

FIG. 5 is an enlarged bottom, front, and left side perspective view thereof.

The broken-line disclosure of a bed and portions thereof in the views is for illustrative purposes only and forms no part of the claimed design.
